UNITED STATES PATENT OFFICE.

KATHRYN M. KAYE, OF NEW YORK, N. Y.

COMBINATION-GARMENT.

1,317,018.

Specification of Letters Patent. Patented Sept. 23, 1919.

Application filed October 24, 1918. Serial No. 259,513.

To all whom it may concern:

Be it known that I, KATHRYN M. KAYE, a citizen of the United States residing at New York City, in the county of New York and State of New York, have invented certain new and useful Improvements in Combination-Garments, of which the following is a specification.

This invention relates to ladies' wearing apparel, and is especially designed to constitute a combination dress or gown.

The prime object of my invention is to provide an efficient combination garment, comprising a dress or gown with an abdominal belt and bust supporter connected thereto, said belt having suitable hose supporters secured thereto and depending therefrom, said garment and combined parts being adapted to sit properly and make a neat and shapely fit.

A further object of the invention is to so construct my combined garment as to properly support the abdomen and bust of the wearer who may be disinclined to wear a tight corset, which is undesirable in athletic and domestic pursuits, and said garment may be also utilized with hygienic results in maternity or negligée gowns.

Another object of the invention is to so construct, the bust supporter, which is used in combination with my dress, that the fastening means secured thereto are adapted to register with and may be readily and detachably secured to suitable means carried by the abdominal belt.

The foregoing and such other objects as may appear from the ensuing description are attained by the combination, arrangement and location of the parts such as hereinafter more fully described, illustrated in the accompanying drawings, and particularly pointed out in the claims appended hereto, it being understood that slight changes in the precise form, proportions, and minor details of the construction may be resorted to without departing from the spirit or sacrificing any of the advantages of the invention.

In the accompanying drawings which form a part of the specification it will be seen that:

Figure 1 is a front elevation of a combination garment embodying my invention, showing the dress or gown opened down the front thereof.

Fig. 2 is a front elevation, showing the bust supporter and abdominal belt secured together, but separated from the dress or gown.

Fig. 3 is a front elevation of the abdominal belt detached, and

Fig. 4 is a front view of the bust supporter detached.

Similar numerals of reference are employed to designate like parts throughout the several figures of the drawings.

In carrying out my invention, such as illustrated, the numeral 1 indicates the dress or gown made of any suitable material or in any desirable style, to which is attached to 70 its inner face at the body portion thereof, in any suitable manner, and designated by the numeral 2' as shown by dotted lines in Fig. 1, an abdominal belt 2 of any preferred construction provided near the upper portion thereof at each side of the vertical center thereof with socket fastenings 4, 4 adapted to receive the snap fastenings 5, 5 carried by the tabs 6, 6, which latter are secured to and are suspended from a suitable 80 bust supporter 7 provided with an extension 8 at each side thereof, and to the end portion of each extension is secured snap fastening means 9, 9 by which the terminals of the said extensions are secured together, and 85 at the upper portion of the said bust supporter, at each side of its vertical center, is secured an inverted V-shaped shoulder strap 10, and to the outer end of each of said straps is rigidly secured a snap fastening 90 11 adapted to be secured at the back of each shoulder to the socket member 12 at the points shown by full and by dotted lines in Fig. 1, said socket members 12 being secured to the inner side of the dress or gown 95 in any suitable or desirable manner; the depending tabs at the lower portion of the bust supporter and the snap fasteners secured thereto being adapted to register with and fasten within the sockets at the front upper portion of the abdominal belt whereby the said bust supporter and belt are securely held together.

The abdominal belt is provided at its bottom portion at each side of the vertical center thereof with suitable depending hose supporters 13, which are firmly secured to said belt at one end, the other end of the supporters being detachably secured to the upper end portion of the hose 14, whereby 110

the hose are properly supported over the limbs of the wearer.

It will be readily perceived that my abdominal belt may be stitched to the inner 5 face of the dress or gown, or may be removably and detachably secured thereto, also said belt may be permanently stitched to or detachably secured to a waist lining or skirt and at the same time, perform all 10 of the functions for which it is intended.

Having thus described my invention, what I claim and desire to secure by Letters Patent is:

1. A combination garment comprising a 15 dress or gown, an abdominal belt secured to the inner face body portion of the dress, a bust supporter removably secured to the inner face shoulder portion of said dress and to the upper portion of the belt, and hose 20 supporters suspended from the bottom portion of the said belt.
2. A combination garment comprising a 25 dress or gown, an abdominal belt secured to the inner face body portion of said dress and provided with securing means near its top front portion at each side of its vertical center, and a bust supporter secured to the rear inner face shoulder portion of the dress and having fastening means secured to the 30 bottom front portion at each side of its vertical center adapted to register and unite with the securing means whereby said bust

supporter, dress and belt are connected together.

3. A combination garment comprising a 35 dress or gown, an abdominal belt secured to the inner face body portion of said dress, a bust supporter provided with fastening means secured to tabs depending from the bottom of said supporter and adapted to be 40 detachably secured to said belt, said supporter having inverted V-shaped shoulder straps at its upper end provided with securing means at their outer ends for attaching the supporter to the rear inner face 45 shoulder portion of the dress.

4. A combination garment comprising a 50 dress or gown, an abdominal belt secured to the inner face body portion of the dress, a bust supporter provided with inverted 55 V-shaped shoulder straps at its upper end, each strap having fastening means at its end for attachment to the rear inner face shoulder portion of said dress, said supporter also having depending tabs at its bottom portion carrying fastening means adapted to register and unite with the securing means carried by the belt for connecting the belt and bust supporter together, and hose supporters suspended from the bottom portion of said belt.

KATHRYN M. KAYE.
